[57] CLAIM

The ornamental design for an actuator assembly for a
portable hand fire extinguisher, as shown and de-
scribed.

DESCRIPTION

FIG. 1 is a front elevation view of the actuator assembly
for a portable hand fire extinguisher;

FIG. 2 is a fragmentary left side view of the fire extin-
guisher;

FIG. 3 is a top plan view of the fire extinguisher;

FIG. 4 is a fragmentary right side elevation view of the
fire extinguisher; and

FIG. 5 is a fragmentary rear elevation view of the fire
extinguisher;

The broken line showing of the tank is for illustrative
purposes only and forms no part of the claimed design.
